Attorney

UNITED STATES PATENT OFFICE.

COMMODORE P. BROWN, OF RONCEVERTE, WEST VIRGINIA.

WRENCH.

Application filed March 23, 1922. Serial No. 545,975.

To all whom it may concern:

Be it known that I, COMMODORE P. BROWN, a citizen of the United States, residing at Ronceverte, in the county of Greenbrier and 5 State of West Virginia, have invented a new and useful Wrench, of which the following is a specification.

The invention relates particularly to that type of wrench in which a slidable jaw is utilized in connection with a sliding rack-catch, and the latter is forced to locked position by 10 means of a cam lever.

The primary object of the invention is to provide a quick action wrench that may 15 readily and with facility be adjusted and locked in adjusted position, and with equal dispatch and convenience may be unlocked for re-adjustment. By the utilization of my invention a comparatively inexpensive tool is 20 provided that is simple in construction, composed of a minimum number of parts, and which may be assembled, or dismantled when required, without the necessity for using tools.

25 In the accompanying drawings I have illustrated one complete example of the physical embodiment of my invention wherein the parts are combined and arranged according to the best mode I have thus far devised 30 for the practical application of the principles of my invention.

Figure 1 is a view in side elevation of a wrench embodying my invention, in unlocked position.

35 Figure 2 is an enlarged, detail view, partly in section, showing the parts in locked position.

Figure 3 is a front edge view of the sliding frame and jaw showing a guide groove 40 or slot in the frame.

Figure 4 is a detail view, looking at the edge of the cam and its lever.

Figure 5 is a similar view looking at the side of the cam and lever.

45 Figure 6 is a view of the rack catch, showing also its spring.

In the preferred form of the invention as shown in the drawings the shank 1 is provided with a rack and fixed head 2 as usual, 50 and the wood handle 3 is secured at the end of the shank by the end nut 4.

The hollow frame 5 is fashioned with the movable jaw 6 complementary to the fixed jaw 2, and the integral frame 5 and its jaw 55 6 are slidable on the shank toward or away

from the fixed jaw, for adjustment in the usual manner.

At the lower end of the frame 5 an inwardly curved extension is formed with two spaced horns 7, 7 between which is fashioned 60 an arcuate guide slot 8 that is open at its lower end, and within the hollow frame just above the curved extension are provided a pair of spaced lugs 9, 9 projecting inwardly from the side walls of the frame and located 65 at the lower open end of the frame. The inner curved faces 10, 10 of the horns 7 are formed as cam faces, and near the extremities of the horns complementary shoulders 11, 11 are provided.

70 The movable jaw is slidable and adjustable on the shank 1 and is held in locked position through the medium of rack catch 12. This rack catch is fashioned as a block with rack teeth to engage the rack on the shank, and is carried by the hollow jaw-frame. On its face opposite the teeth the rack catch is fashioned with a concave cam face 13, disposed opposite to the cam face 10 of the horns 7, and a lug or shoulder 14 on the rack catch is adapted to abut against the shoulder or lug 11 on the horns to limit lateral movement of the rack catch. The lower end of the rack catch rests and is slidable on the extremity of the two horns, and the rack catch is movable between the shank and horns, but limited at one side by the shank, and at the other side by the shoulders 11 of the horns.

80 At its upper end the rack catch is fashioned with a socket to receive the end of a curved leaf spring 15, which projects up into the frame and is fixed to the rack catch in such position as to frictionally engage the edge of the shank when the rack catch is held in locked position. In Figure 2 the 85 spring is in close engagement with the teeth of the shank, but when the catch is released, the spring, due to its resiliency, will force the catch away from the shank, the lower end of the spring being guided by the two lugs 9, 9 and the end of the catch block sliding on the extremity of the horns 7.

90 The rack catch is forced into engagement with the teeth of the shank by turning the cam locking key 16 which is interposed between the cam face 13 of the rack catch and the cam faces 10 of the two horns 7. The key is fashioned with oppositely disposed 95 convex cam faces 17 and 18 to co-act re- 100

105

110

spectively with the concave faces 13 and 10 and the key is rotatable with an arc of about ninety degrees. An operating lever 19, which is comparatively short and adapted to be manipulated by the thumb, projects from the key and is positioned within the guide slot 8 of the frame. The lever, which is thus retained in the guide slot, holds the key in operative position against endwise movement, and the key is confined between the rack catch and horns. By pressure of the thumb against the projecting end of the lever the key is turned and the movement of the lever is guided by the walls of the slot 8.

In Figure 1 the lever 19 is turned to unlocked position. By turning the lever down, parallel, or approximately parallel with the shank, the rack catch is forced into engagement with the teeth of the shank as seen in Figure 2, and the jaw 6 is thus held in rigid relationship with the fixed jaw 2. The rack catch is forced to locked position against the tension of the spring 15 so that, when the lever is turned to unlocked position to free the rack catch, the spring forces the catch from engagement with the shank.

When assembling the parts, before the handle 3 is placed in position on the shank, the frame is slipped over the end of the shank, the key and its lever are placed in position in the frame as in Figure 1, and then the spring 15 is entered between the bifurcated extension and shank. The catch is pressed (against tension of its spring) into and held in contact with the teeth of the shank and then the frame is slipped over

the catch. The spring is now released and draws the catch to inoperative position, holding the key as in Figure 1. To dismantle the tool this operation is reversed. Thus the construction and operation of the several parts of the wrench are simplified, the assembly and dismantling of the elements of the tool may be quickly accomplished, and the movable parts are retained in their operative relationship for facile manipulation.

The several parts of the tool, including the locking key, may with facility be manufactured and finished, as in a milling machine, thus insuring a close and accurate fitting of the co-operating parts, and permitting quantity production of the tool.

From the above description taken in connection with my drawings it will be apparent that I have provided a simple, but efficient device for performing its required functions, and which fulfills the purposes and objects of my invention.

Having thus fully described my invention what I claim and desire to secure by Letters Patent is:—

The combination with a shank and fixed jaw, of a slidable jaw and frame, a bifurcated extension on said frame having an inner cam face, a spring pressed sliding-catch having a complementary cam face and retained within the frame, a key located between said cam faces, cam faces on opposite sides of said key for engagement with the first mentioned cam faces, and a lever on the key guided in the bifurcated extension.

COMMODORE P. BROWN.
